UNITED STATES PATENT OFFICE.

ALBERT S. CARTER, OF DENVER, COLORADO.

DESIGN FOR A BADGE.

SPECIFICATION forming part of Design No. 24,869, dated November 12, 1895.

Application filed July 1, 1895. Serial No. 554,648. Term of patent 7 years.

To all whom it may concern:

Be it known that I, ALBERT S. CARTER, a citizen of the United States of America, residing at Denver, in the county of Arapahoe and State of Colorado, have invented a certain new and original Design for Badge Emblems; and I do declare the following to be a full, clear, and exact description of the invention, such as will enable others skilled in the art to which it appertains to make and use the same, reference being had to the accompanying drawing, which forms a part of this specification.

My invention relates to a new and original design for badge emblems; and it consists of the features hereinafter described and claimed, all of which will be fully understood by reference to the accompanying drawing, in which is illustrated an embodiment thereof.

The drawing represents a front view of the emblem on a scale very much enlarged.

The leading feature of the design consists in the special representation and arrangement shown of an ax sticking in a log pro-

vided with several stumps of branches, one 25 of which projects slightly above the handle of the axe, the latter being so applied to the log that the handle occupies a position parallel or approximately parallel with the log, whereby a device, elongated or rectangular 30 in outline or configuration, is formed.

I am aware of Patent No. 21,718, in which an ax sticking in a log is shown in connection with other features, making a design of circular shape. Hence I do not claim the ax 35 and log broadly, but only when arranged to produce a design of the special shape shown.

Having thus described my invention, what I claim is—

The design for a badge, or similar article, 40 as herein shown and described.

In testimony whereof I affix my signature in the presence of two witnesses.

ALBERT S. CARTER.
